UNITED STATES PATENT OFFICE.

JABEZ JENKINS, OF PHILADELPHIA, PENNSYLVANIA.

DYNAMO-ELECTRIC MACHINE.

SPECIFICATION forming part of Letters Patent No. 350,000, dated September 28, 1886.

Application filed April 5, 1886. Serial No. 197,757. (No model.)

To all whom it may concern:

Be it known that I, JABEZ JENKINS, a citizen of the United States, residing at the city and county of Philadelphia, in the State of Pennsylvania, have invented new and useful Improvements in Dynamo-Electric Machines, of which the following is a specification.

This invention relates to drum-armatures for dynamo-electric machines; and my improvements consist in the construction and system of winding the coil, as hereinafter fully described and claimed.

In the drawings, Figure 1 represents an end view of the drum-armature; and Fig. 2, a longitudinal section through the same, taken on the line *x x* of Fig. 1.

A is a revolving shaft upon which the drum-armature is mounted.

B are two circular heads, of hard wood or other suitable material, which form the ends of the drum and are secured to the said revolving shaft by means of the flanges *b*.

C are horizontal strips placed around the circumference of the said heads and secured to them by screws *c*. Any even number of strips may be used, as found convenient and according to the size of the machine, and the strips may be connected to the heads by hoops or bands, or in any other convenient manner.

D are cores, formed of a number of soft-iron wires, the core being one-fourth to three-eighths of an inch in diameter, and about two inches in length, though I do not confine myself to this size. Each core contains a sufficient number of wires to fill the hole *c'* when placed in it, and the wires are of sufficient length to project some distance through the inside of the strip, where they are fastened or bound by clamps or otherwise, and extend outward through the recess *c''* to the surface of the drum.

E is the insulated copper wire of the coil. This wire is started at the shaft, and is carried outward to one end of a strip. It then is bent and is carried horizontally to the first core.

The horizontal wire is then wound around the outer end of the said core for about one-third of its length and back again, forming the spiral *e*, though I do not limit myself to two layers. 55 This spiral fits into the recess *c'* in the strip *C*. The wire is then carried horizontally along the surface of the strip to the next core, and is wound about it into another similar spiral, and so for all the cores. The horizontal parts of the coil-wire upon the surface of the drum are marked *e'*. On reaching the end of the drum the wire is carried across the end of it, on the outside of the head, to the strip upon the opposite side, and a second series of spirals, *e*, and horizontal portions *e'*, is again formed similar to that before described. 60 All the spirals are wound in the same direction, and the circuit is completed by bringing the end of the wire back to the shaft at the 70 same end of the drum where it started. The ends of the wire *E* are each connected with a segment of the commutator in the usual manner. In a similar manner each remaining pair of strips in the drum is provided with a series 75 of radial cores of soft-iron wires having their ends surrounded by spirals which are connected together by horizontal wires passing round the drum. The drum is made to revolve between the poles of the dynamo in the ordinary 80 manner, and the commutators, brushes, and other parts differ in no essential particular from those commonly used in connection with drum-armatures. When the drum is rotated in the magnetic-field a current of superior force 85 is generated by this arrangement.

I claim—

1. In a drum-armature, the combination of a revolving shaft, circular heads secured upon the said shaft, horizontal strips connecting the 90 said heads and having a line of holes in them, cores of soft iron passing through the said holes radially to the shaft, and a circuit-wire wound horizontally about the drum and comprising in its length a series of spirals wound 95 around the said cores, substantially as and for the purpose set forth.

2. In a drum-armature, the combination of a revolving shaft, circular heads secured upon the said shaft, horizontal strips connecting the 100 said heads and having a line of holes in them, the outer ends of which are counterbored to

form pockets, a series of cores of soft iron passing through the said holes radially to the said shaft, a series of spirals placed in the said pockets and wound around the said cores, and 5 a circuit-wire wound horizontally about the drum and including the said spirals in the circuit, substantially as and for the purpose set forth.

3. The series of cores D, each formed of a 10 bound bundle of soft-iron wires, in combination with the longitudinal drum-strips C, through which said cores extend radially from the outside surface toward the center of the drum, and a circuit-wire, E, wound around the outer 15 end of each core, beginning at one end of the drum and extending over its opposite end in continuous succession from end to end on opposite sides of said drum and terminating at the starting end thereof, substantially as described, for the purpose specified.

4. In a drum-armature, the combination of 20 a series of soft-iron cores, each core formed of a bundle of soft-iron wires, with the circuit-wire E forming a coil-binder for each core-bundle, and a means whereby each core is secured 25 to the drum in longitudinal lines.

5. In a drum-armature for dynamo-electric machines, the combination of a series of separate soft-iron cores arranged in longitudinal lines, with the circuit-wire wound around each 30 core in the same direction from end to end of the drum, crossing the end of the latter and returning on its opposite side around a similar series of cores, substantially as described, for the purpose specified.

6. The combination, in a drum-armature for 35 dynamo-electric machines, of a series of soft-iron cores, each formed of a bundle of wires bound separately at their inner ends, with a circuit-wire connecting and binding the several cores in separate bundles at their outer ends, and a suitable socketed carrier, to which the said series of cores are bound by the circuit-wires, substantially as herein set forth.

In testimony whereof I have hereunto set 40 my hand in the presence of two subscribing witnesses.

JABEZ JENKINS.
